UNITED STATES PATENT OFFICE.

ALBERT E. ROBERTS, OF NORWALK, OHIO, ASSIGNOR TO NOADIAH P. BOWLER, OF CLEVELAND, OHIO.

OVERSHOE.

No. 808,948.

Specification of Letters Patent.

Patented Jan. 2, 1906.

Application filed April 18, 1904. Serial No. 203,540.

To all whom it may concern:

Be it known that I, ALBERT E. ROBERTS, a citizen of the United States, residing at Norwalk, in the county of Huron and State of Ohio, have invented a certain new and useful Improvement in Overshoes, of which the following is a full, clear, and exact description, reference being had to the accompanying drawings.

- This invention is an improvement on the overshoe shown in my Patent No. 736,156 and granted August 11, 1903. The overshoe shown is characterized by having a relatively high heel portion, a low front portion extending a little higher than the sole of the corresponding shoe, and a continuous non-elastic band embedded in the overshoe and extending around both its heel and front portion and adapted at the front portion to lie over the projecting shoe-sole. Such an overshoe is now on the market and is giving good satisfaction. It has, however, two limitations which the present invention is designed to overcome—namely, in some shoes the shank of the overshoe does not hug the sides of the shoe with the desired tightness, and, second, when the weight is borne entirely on the toe of the foot, as in walking upstairs, it sometimes happens that the heel of the shoe comes out of the overshoe. My present invention at once remedies both of these defects by bringing the non-elastic band inward along the sole of the overshoe-shank, whereby the band is anchored thereat, and there are, in effect, two loops, one around the front portion and one around the heel portion, and between them, on each side of the overshoe, is the elastic side shank. The result of this is that the side shank is always held snugly against the side of the shoe. Moreover, being elastic it allows the overshoe to be stretched when the shoe is inserted, and this results in the overshoe tightly holding its place on the shoe irrespective of where the weight is borne. The band or loop in leading from the shank rearward passes well up on the heel portion of the overshoe, wherefore it secures a firm grip above the rearmost bulge of the heel-counter of the shoe. The double loop or band I prefer to provide of one cord by crossing it on itself in the sole of the shank, though the band need not thus cross, as much of the advantage would be obtained by making
- each loop of a separate cord, the ends being vulcanized into the sole at the shank of the rubber, or the result might be obtained by allowing each course of the band to stay on one side of the shank, being simply bowed inward at the shank-sole and there held. The band is an inelastic cord and is vulcanized into the body of the overshoe. It thus prevents stretching along the line of the cord; but the side shanks of the overshoe being relieved of the cord allow stretching at this point, which enables the overshoe to make a tighter and better fit than heretofore.
- The drawings clearly illustrate my invention.
- Figure 1 is a perspective view of the overshoe. Fig. 2 is a vertical longitudinal section thereof. Figs. 3 and 4 are cross-sections on the correspondingly-numbered lines of Fig. 2. Fig. 5 is a sectional plan of the sole of the shank portion, as indicated by the line 5 5 of Fig. 2; and Figs. 6 and 7 are similar views showing modified methods of forming the loops into the sole.
- The overshoe may most conveniently be considered as consisting of a front portion, a heel portion, and a shank portion connecting the two, though of course these portions merge one into the other.
- A represents the shoe-sole; B, the wall of the forward portion, which rises a little higher than the sole of the shoe which the overshoe is adapted to incase.
- C represents the heel portion, and D the shanks.
- The non-elastic band is indicated by E. It is near the top of the portion B of the overshoe and in the portion C extends diagonally upward from the shank to near the top of the heel. At the shank this band passes inward along the sole, so as to allow the elasticity of the rubber at the shank to be effective. This inward deflection of the band is preferably caused by crossing the band on itself within the sole of the shank portion, as shown in Fig. 5. The band might be made of two separate loops, each terminating in the shank, as illustrated in Fig. 6, or the single band might be simply bowed inwardly at the shank, as shown in Fig. 7.
- With the overshoe as described it will be seen that the rear loop or band passing around the heel high up on the back part and

down under the shank-sole and vulcanized into the body of the overshoe prevents individual expansion of this part and holds the heel part of the rubber firmly to the heel part 5 of the inserted shoe. The front loop or band passing around the front part of the sides of the rubber and vulcanized therein near the top and also vulcanized in the sole part of the shank prevents expansion of the forward part 10 of the rubber and locks it to the inserted shoe. The elastic shank parts of the rubber between the heel portion and the forward portion allow the non-elastic loop of the heel part to pass over the bulge of the heel of the 15 inserted shoe, so that after the shoe is inserted the retractile force of the stretched shank insures the overshoe being firmly held to the shoe. At the same time the side shanks being relieved of the elastic band are not pulled 20 out straight, but may be curved inward to lie snugly along the side of the shoe, as indicated by the curved edges of the sole in Fig. 5.

It is not necessary for the cord to cross the shank part in the sole of the shoe, though this 25 is preferred, for any deflection of the cord from the side shanks, if it is vulcanized into the sole part so that it will hold, will allow the extension of the side shanks so that a tighter hold may be obtained on the inserted shoe.

30 I claim—

1. As a new article of manufacture, an overshoe provided with longitudinally-elastic side shanks and with loops restraining the heel and the front portions of the upper.
2. An overshoe having a non-elastic band 35 passing around both its front and rear part and deflected at the shank to prevent the band restraining the elasticity of the side shanks.
3. An overshoe having a non-elastic band 40 vulcanized in the overshoe and passing around the front portion and then deflecting into the sole of the shank portion, and a non-

elastic band passing around the heel portion and deflecting inwardly into the shank. 45

4. In an overshoe having a relatively high heel portion and a relatively low front portion, a non-elastic band vulcanized in the upright walls of the overshoe except at the shank portion, and at this portion passing into 50 the sole of the overshoe and there vulcanized in place.

5. An overshoe having a relatively high heel portion and a relatively low front portion, a non-elastic loop vulcanized in the overshoe and passing around the front portion and then into the sole of the shank portion, and a 55 non-elastic loop passing around the heel portion high up on the heel portion to take above the rearmost bulge of the inserted shoe. 60

6. As a new article of manufacture, an overshoe having a non-elastic band vulcanized in the side walls of the front and heel portion of the overshoe, and crossing itself within the sole of the shank portion. 65

7. As a new article of manufacture, an overshoe having a non-elastic band vulcanized in the side walls of the front and heel portion of the overshoe and crossing itself within the sole of the shank portion, said band on the 70 heel portion leading diagonally upward from the sole to near the top of the heel, the band being vulcanized in place throughout.

8. As a new article of manufacture, an overshoe having two non-elastic loops, one vulcanized into the side walls of the front of 75 the overshoe, and the other vulcanized into the side walls of the heel of the overshoe, and both vulcanized into the sole of the overshoe at the shank. 80

In testimony whereof I hereunto affix my signature in the presence of two witnesses.

ALBERT E. ROBERTS.
